UNITED STATES PATENT OFFICE.

ERNST KOCHENDOERFER, OF FRANKFORT-ON-THE-MAIN, GERMANY.

PROCESS FOR MANUFACTURING NITROGEN COMPOUNDS.

1,207,416.

Specification of Letters Patent.

Patented Dec. 5, 1916.

Application filed March 26, 1913. Serial No. 756,864.

To all whom it may concern:

Be it known that I, ERNST KOCHENDOERFER, a subject of the Emperor of Germany, residing at Frankfort-on-the-Main, Germany, have invented certain new and useful Improvements in Processes for Manufacturing Nitrogen Compounds, of which the following is a specification.

This invention relates to the manufacture 10 of nitrogen compounds from the gases generated by the carbonization of distiller's wash and the like nitrogen carrying substances.

It has particular relation to the well-known cyanization of certain gases, resulting 15 from the carbonization of distiller's wash and the like, by means of overheating. Said gases have a considerable content of nitrogen, which renders them very valuable 20 for the manufacture of nitrogen compounds, such as cyanogen compounds and ammonia.

There are quite a number of processes for such manufacture, but these processes are not sufficiently satisfactory because the yield 25 of nitrogen compounds is considerably below that to be expected on theoretical calculations. In my U. S. Letters Patent, No. 1,165,358, patented Dec. 21, 1915, entitled "Processes for manufacturing nitrogen 30 compounds," I have pointed out in a rather detailed way such gases as result from the carbonization of distiller's wash and these gases are hereinafter simply called "gases."

In the present state of the art of cyanizing 35 gases generated by the carbonization of distiller's wash and other like gases by superheating the same, little attention has been paid either to the material or to the surfaces of the channels through which the gases are 40 passed to be superheated. I have discovered, however, that in the art of cyanizing such gases, due attention must be given to the material of which the channels are made and that the economy of the cyanizing process 45 is considerably reduced if the surface of the channels is rough and porous. I have furthermore discovered that this injurious effect caused by the rough and porous surfaces of the superheater-channels may be 50 counteracted by increasing the speed of the gases through the channels in such a way that each of the molecules of gas is in contact with the rough and porous surfaces for only a very short time. Finally I have also 55 discovered that the injurious effects caused by the catalytic action of the surfaces of the

superheater-channels are more easily avoided if the superheater-channels are made from a material giving an acid reaction instead of from a material of basic character, 60 although even with material of basic character almost theoretical yields of nitrogen compounds may be obtained if high temperatures and great speed of the gases through the channels are resorted to. 65

By reason of my invention I have now succeeded in overcoming the well-known difficulties of the other processes of cyanizing gases provided the operations are carried out in the way described below. 70

In practising my invention the inside of the channels of a superheater of any of the well-known constructions is lined with any suitable fire proof material, as for instance the well known Dinas-stones which 75 consist chiefly of quartz. In selecting this lining material I do not attribute particular importance to the physical condition of said Dinas-stones inasmuch as it is immaterial whether the smoothness of their surfaces as 80 well as the density of the material is more or less perfect.

In order to counteract the decomposition caused by the rough surfaces as well as by the porosity of the stones, it is essential to 85 first establish the measurements of the cross-section of the channels in view of the composition of the distiller's wash to be carbonized, and then to find out that particular speed of the gases which is most favorable 90 for the elimination of the decomposing effect of the catalytic action of the surfaces. The speed of the gases cannot be permanently maintained at the same rate but is 95 always subject to the composition of the distiller's wash which is known to vary greatly.

I have found it advantageous to pass the gases, which are to be cyanized and which contain the nitrogen mostly in the form of pyridin compounds, through the superheater channels at a speed not exceeding 7 meters per second; care must be taken during this operation that the gases at this speed actually attain the high temperature required. Gases containing the nitrogen 105 preferably in the form of amino compounds may be treated at the same temperature while passing the superheater channels at a much higher speed, the speed in this case being 10 meters and even more per second. 110

The operations described above offer the further advantage of permitting a direct

passage of the gases from the carbonizer into the superheater-channels the gases not sustaining a change in their composition during such passage.

5 Up to the present it has been considered necessary to separate the nitrogenous tar from the gases on their travel from the carbonizer to the superheater and to separately cyanize the so-obtained tar; another 10 modification of the cyanizing process has consisted in the perfect separation of the gases into those liable to undergo cyanization and those not undergoing cyanization.

It is conceded that the two modifications 15 mentioned above really result in a higher yield of nitrogen compounds, but such yields were still considerably below the theoretical one and are not in proportion to the expense entailed by carrying out the cumbersome 20 operations referred to.

The gases undergoing cyanization constitute only a rather small part of the gases leaving the carbonizer and though they are accompanied by a great excess of water 25 vapor and other gases, not undergoing cyanization and only retarding the reaction, yet I am able by my invention to convert the former kind of gases into cyanogen compounds and ammonia with an almost theoretical 30 yield, the more valuable cyanogen compounds, however, prevailing in the obtained products to a considerable extent, thus increasing the economical importance of my invention.

35 The economical results of my process are rather considerable inasmuch as I am able to avoid several cumbersome operations by the practice of my new process; the improved results obtained thereby enable me 40 also especially to take advantage of the heat contained in the gases when leaving the carbonizer and finally to obtain a most satisfactory yield of cyanogen compounds.

The technical operation of my new process 45 depends a great deal on the carbonization, which is governed by the composition of the raw material to be gasified. If the carbonization occurs at a high temperature any condensation of compounds may be prevented 50 by carefully insulating the connection pipes between the carbonizer and the superheater, this precaution being assisted favorably by installing connection pipes of proper dimensions.

55 In case a raw material is to be gasified which will give the greatest yield of cyanizable gases only when carbonized at a relatively low temperature, the gases and vapors will accordingly be of low temperature when 60 leaving the carbonizer; it is obvious that the operation of the carbonizer is very important for the regulation of the whole process, for by slackening the fire under the carbonizer I can first of all reduce the temperature 65 of the gases, if necessary, and by thus

controlling the fire as pointed out above I can furthermore also regulate the speed of the gases as required by the relation between the same and the heating surface of the channels. On the other side the higher 70 I heat the carbonizer the greater will be the pressure of the gases and consequently also their traveling speed, while of course a reduction in the supply of heat will ultimately also reduce their speed accordingly. If it 75 is advisable that the gases leaving the carbonizer have a low temperature, the connection pipe between the carbonizer and superheater must be provided with some suitable means which will permit of immediately heating said pipe sufficiently so as to prevent any segregation of liquids within the pipe. This feature of preventing any liquefaction of gases by submitting the same to heat, may be successfully carried out by 80 using waste heat from the many sources existing in cyanid factories.

For the further elucidation of my invention a construction of the apparatus preferred for carrying out the process is illustrated, by way of example, in the accompanying drawing, which is a vertical sectional view partly diagrammatic of said apparatus. The distiller's wash, for example, is carbonized in the fire clay retorts A and 90 the distillation gases escape through connection pipes B into the main pipe C whence they travel into a superheater channel D surrounded by a suitable mantle E made of fire clay bricks or other suitable material. 95 As the superheater channel D is heated to a high temperature, flues F of sufficient width are interposed between the mantle E and channel D and an inlet G and exit H is provided for the heating gases. The distillation 100 gases are cyanized while passing through the hot superheater channel and leave through exit I to be further treated 105 to assume marketable form.

The process as described is particularly 110 valuable in manufacturing nitrogen compounds, such as cyanogen compounds and ammonia, and under the term "nitrogen compounds" as used in the claims, I mean to include cyanogen and ammonia, as well 115 as other compounds coming within that broad designation.

What I claim and desire to secure by Letters Patent is:

1. In the process of manufacturing nitrogen compounds from the gases generated by the carbonization of distiller's wash and the like nitrogenous substances, carbonizing said substance, superheating the resulting gases and reducing the time of contact of said 120 gases with the superheating surface by increasing the speed of said gases over said surface.

2. In the process of manufacturing nitrogen compounds from the gases generated by 130

the carbonization of distiller's wash and the like nitrogenous substances, carbonizing said substance, superheating the resulting gases, reducing the time of contact of said gases with the superheating surface by increasing the speed of said gases over said surface and varying said increased speed according to the composition of said gases.

3. In the process of manufacturing nitrogen compounds from the gases generated by the carbonization of distiller's wash and the like nitrogenous substances, carbonizing the substance, superheating the resulting gases and controlling the time of contact of said 10 gases with the superheating surface by varying the ratio between the superheating area and the speed of the gases passing over the same.

4. In the process of manufacturing nitrogen compounds from the gases generated by 20 the carbonization of distiller's wash and the like nitrogenous substances, carbonizing the substance, superheating the resulting gases, controlling the time of contact of said gases with the superheating surface by varying 25 the ratio between the superheating area and the speed of the gases passing over the same and varying said speed according to the composition of said gases.

In testimony whereof I have signed this 30 specification in the presence of two subscribing witnesses.

ERNST KOCHENDOERFER.
